SAW FILING MACHINE

Rolo S. Ewers, Glendale, Ariz.

Application June 2, 1942, Serial No. 445,489

3 Claims. (Cl. 76—31)

The present invention relates to new and useful improvements in saw filing machines, and has for its primary object to provide, in a manner as hereinafter set forth, a device of this character comprising supporting means for a manually operable file of a novel construction and arrangement whereby said file may be expeditiously and accurately adjusted to any desired position for meeting various conditions.

Another important object of the invention is to provide a saw filing machine of the aforementioned character comprising depth and width gauges of unique construction, whereby said gauges may be accurately adjusted and, when not in use, conveniently swung to an out-of-the-way position.

Other objects of the invention are to provide a saw filing machine of the character described which will be comparatively simple in construction, strong, durable, highly efficient and reliable in use, compact, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of a saw filing machine constructed in accordance with the present invention.

Figure 2 is a cross-sectional view, taken substantially on the line 2—2 of Figure 1.

Figure 3 is a bottom plan view of the file supporting carriage.

Figure 4 is a cross-sectional view, taken substantially on the line 4—4 of Figure 2.

Figure 5 is a cross-sectional view, taken substantially on the line 5—5 of Figure 2.

Figure 6 is a detail view in horizontal section, taken substantially on the line 6—6 of Figure 2.

Figure 7 is a detail view in horizontal section, taken substantially on the line 7—7 of Figure 2.

Figure 8 is a detail view in perspective of the slidably mounted file supporting member.

Figure 9 is a view in longitudinal section through the upper portion of the device, taken substantially on the line 9—9 of Figure 1.

Figure 10 is a view in front elevation of the saw clamping means.

Figure 11 is a detail view in vertical section through the means for supporting one end of the file.

Figure 12 is a detail view in vertical section through a portion of the carriage.

Referring now to the drawings in detail, it will be seen that the embodiment of the invention which has been illustrated comprises a supporting structure 1 of suitable metal. The supporting structure 1 includes a pair of angular brackets 2 comprising base members 3 which may be firmly secured in any suitable manner to a bench or other support. Inclined bars 4 are secured at an intermediate point, as at 5, on the upper portions of the brackets 2, which bars are capable of pivotal adjustment to any desired inclination.

A saw clamp 6 is mounted on one end portion 15 of the bars 4. The clamp 6 includes a pair of substantially U-shaped members 7 which are mounted for swinging adjustment on a rod 8 which extends between the bars 4. Mounted on the rod 8 is a tube 10 (see Fig. 1). It will be observed that one end portion of the members 7 is mounted on the rod 8 between the ends of the tube 10 and the inner sides of the bars 4. Nuts 11 are threaded on the end portions of the rod 8 for clamping the members 7 in adjusted position between the bars 4 and the tube 10. Extending between these end portions of the members 7 is a stationary jaw 12.

At their other ends, the members 7 terminate in forwardly projecting hooks 13. Bolts 14 are mounted on these end portions of the members 7. Levers 15 are pivotally and removably mounted on the bolts 14, said levers being operable in the hooks 13. Notches or slots 16 in the levers 15 (see Fig. 6) accommodate the pivot bolts 14. A swinging jaw 17 is mounted on one end of the levers 15 for coaction with the stationary jaw 12 for clamping a saw 18 therebetween. Rubber blocks 19 are mounted in the hooks 13 and engaged with the levers 15 in a manner to yieldingly engage the jaw 17 with the saw 18. Cam levers 20 are pivotally mounted, as at 21, on the lower portions of the members 7 and engaged with the lower end portions of the levers 15 for positively moving the jaw 17 toward the stationary jaw 12 for clamping the saw 18 therebetween. Coil springs 22 are connected to the lower portions of the levers 15 for maintaining said levers in engagement with the cam levers 20.

Fixed on the other end portions of the bars 4 is a tube 23 (see Figs. 2 and 9). A rod 24 extends through the tube 23 and terminates in threaded end portions which project beyond the ends of said tube. Mounted for swinging adjustment on the projecting end portions of the rod 24 is a pair of arms 25. Nuts 26 are threaded on the

end portions of the rod 24 for clamping the arms 25 in adjusted position against the ends of the tube 23. Extending between the free end portions of the arms 25 is a track 27 in the form of a metallic rod.

A file carriage 28 is operable on the track 27. The carriage 28 includes a platform 29 having mounted on its ends pairs of oppositely inclined rollers 30 which travel on the track 27. Depending from the platform 29 (see Figs. 2 and 3) is a hanger 30' having pivotally mounted thereon a shaft 31 which is adapted to extend transversely beneath the track 27. A flanged roller 32 is journaled on the shaft 31 and engaged beneath the track 27 for travel thereon. A coil spring 33 from the platform 29 is connected to the free end of the shaft 31 for engaging the roller 32 beneath the track 27. The elements 30' to 33, inclusive, constitute means for retaining the carriage 28 on the track 27.

Pivotedly mounted at an intermediate point for swinging adjustment on the platform 29 is a frame 34. The frame 34 includes a pair of angle iron bars 35. A block or plate 36 on one end portion of the bars 35 secures said bars together in spaced, parallel relation. As illustrated to advantage in Figure 12 of the drawings, a bar 37 extends between the bars 35 at an intermediate point. A threaded pivot pin 38 is anchored in the bar 37 and extends downwardly therefrom through an opening which is provided therefor in the platform 29. A hand operated nut or the like 39 is threaded on the pin 38 and engaged beneath the platform 29 for frictionally securing the frame 34 in pivotally adjusted position on said platform.

Rising from the bars 35 at an intermediate point is a post 40. A substantially U-shaped slide 41 is mounted for reciprocation on the post 40 in parallelism with the bars 35, said slide including a comparatively long lower leg 42. Secured by a set screw 43 (see Fig. 4) on the free end portion of the leg 42 of the slide 41 is a bearing 44 comprising, in its lower portion, a substantially semi-circular, graduated recess 45. The recess 45 accommodates a rotatably adjustable bushing 46 (see Fig. 2) which is fixed on one end portion of a file 47 of triangular cross-section. This end portion of the file 47 includes a tang 48 on which a handle 49 is mounted. A marked disc 50 is fixedly mounted between the handle 49 and the bushing 46 for coaction with the graduations on the bearing 44 to facilitate rotatably adjusting the file 47 to the desired position. A strap 51 has one end anchored to the bearing 44 and its other end detachably and adjustably connected to said bearing by means including a threaded shank 52 which passes through an apertured ear or lug 53 which is provided therefor on said bearing. A wing nut 54 is threaded on the shank 52. The strap 51 passes under the bushing 46 for clamping the file 47 in adjusted position. An angular bracket 55 (see Fig. 11) is secured by a set screw 56 at an intermediate point on the leg 42 of the slide 41 for supporting the other end of the file 47. Toward this end, the bracket 55 includes a socket 57 for the reception of the file 47.

Mounted beneath the front portions of the bars 35 is a pair of depth gauges 58 which are engageable on the teeth of the saw 18, which saw, it will be noted, is secured in the clamping unit 6 in an inverted position. The depth gauges 58 include metallic bars 59 having upturned rear end portions 60 which are engaged beneath the 70

bars 35. Headed pins 61 are secured to the rear portions of the bars 59 and pass slidably through the bars 35. Coil springs 62 are engaged with the pins 61 for yieldingly urging the bars 59 upwardly or away from the saw 18. Adjusting screws 63 for the bars 59 are mounted vertically in the bars 35. The adjusting screws 63 are provided with reduced teats 64 on their lower ends which are engageable in openings provided therefor in the depth gauge bars 59. This permits the bars 59 to be conveniently disconnected from the adjusting screws 63 and swung around to an out-of-the-way position when the depth gauges 58 are not in use. Resilient clips 65 on the bars 35 frictionally secure the adjusting screws 63 in adjusted position.

Pivotedly mounted for swinging movement in a vertical plane on the post 40 and extending forwardly therefrom is an arm 66. Mounted on the 20 free portion of the arm 66 and depending therefrom is a width gauge 67 which, as best seen in Figure 5 of the drawings, is engageable between the teeth of the inverted saw 18. A coil spring 68 is connected to the arm 66 for yieldingly engaging the gauge 67 with the saw.

A pair of brackets 69 are mounted on the bars 35 and project longitudinally from the forward ends thereof. The brackets 69 include, on their projecting end portions, upturned ears 70 in which transverse adjusting screws 71 for the gauge 67 are threadedly mounted. Referring again to Figure 5 of the drawings, it will be noted that the gauge 67 is engaged with the inner ends of the adjusting screws 71. Resilient clips 35 72 on the brackets 69 frictionally secure the screws 71 in adjusted position. By removing one of the securing elements 73 (see Fig. 1) of each of the brackets 69, said brackets with the adjusting screws 71 thereon may be swung around to an out-of-the-way position on the bars 35 when the width gauge 67 is not being used. This feature of the gauge devices permits a clear or substantially unobstructed view of the saw to be had.

It is thought that the operation of the device will be readily apparent from a consideration of the foregoing. Briefly, the saw 18 to be filed is secured in position in the clamping unit 6 and the various adjustments are made to properly position the file 47 relative to the saw. The file 47 is then moved back and forth across a tooth of the saw, the slide 41 supporting said file during this operation. Every other tooth of the saw is filed, after which said saw is reversed in the clamping unit 6. The desired adjustments are again made and the operation is repeated. The saw 18 is removed from the clamping unit 6 by swinging the cam levers 20 upwardly.

It is believed that the many advantages of a saw filing machine constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

1. A saw filing machine of the character described comprising a supporting structure including a pair of bars pivotally mounted, at an intermediate point, for swinging adjustment in a vertical plane, means for mounting a saw to be filed on one end of the bars, a track on the other ends of said bars, a carriage operable on

said track, a slide operable on said carriage, and a file mounted on said slide and engageable with the saw.

2. A saw filing machine of the character described comprising a supporting structure including a pair of bars pivotally mounted, at an intermediate point, for swinging adjustment in a vertical plane, a clamping unit on one end of the bars for receiving and securing a saw to be filed, a track mounted for swinging adjustment on the other ends of the bars, a carriage operable on said track, a frame pivotally mounted for swinging adjustment on said carriage, a slide operable on said frame, and a file mounted on said slide and engageable with the saw.

3. A saw filing machine of the character de-

scribed comprising a supporting structure, a clamping unit mounted on said supporting structure, said clamping unit including a pair of substantially U-shaped members secured to the supporting structure, a stationary jaw fixed on one end of said members, a pair of levers pivotally mounted, at an intermediate point, on the other end portions of the members, a movable jaw on one end of said levers cooperable with the stationary jaw for receiving and securing therebetween a saw to be filed, cam levers pivotally mounted on the members and operatively engaged with the other end portions of the levers for swinging the movable jaw toward closed position, and a file movably mounted on the supporting structure and engageable with the saw.

ROLO S. EWERS.
